[57] CLAIM

The ornamental design for a Christmas tree transport cart, as shown and described.

DESCRIPTION

FIG. 1 is a side elevational view of a Christmas tree transport cart showing my new design, the broken lines are for illustrative purposes only and form no part of the claimed design;

FIG. 2 is a front elevational view thereof;

FIG. 3 is a rear elevational view thereof;

FIG. 4 is a top plan view thereof;

FIG. 5 is a top plan view of a second embodiment of the Christmas tree transport cart, with an optional grid frame in place;

FIG. 6 is a bottom plan view of FIG. 1;

FIG. 7 is a side elevational view of FIG. 5;

FIG. 8 is a front elevational view of FIG. 5; and,

FIG. 9 is a rear elevational view of FIG. 5.
